[57] **ABSTRACT**

An electrochemical process for the anodic alkylation of lead using $KAlR_2X_2$ and RX , where R is selected from the group consisting of ethyl, propyl, isopropyl, butyl and isobutyl and X is selected from the group consisting of bromine, chlorine and iodine, with a lead anode and an inert conductor as the cathode.

ANODIC PROCESS FOR THE PREPARATION OF TETRAALKYL LEAD COMPOUNDS

BACKGROUND OF INVENTION

1. Field of Invention

This invention relates to the preparation of tetraalkyl lead compounds and more particularly to an anodic electrochemical process wherein $KA_1R_2X_2$, in the presence of RX , is reacted at a lead anode to produce tetraalkyl lead compounds.

2. Description of Prior Art

There are many procedures disclosed in the art for the production of organolead compounds, particularly the commercial product, tetraethyllead. These procedures have all suffered particular disadvantages, among which are the cost and the yield of the organolead product produced. For example, the commercial process used today involves the reaction of ethyl chloride with a sodium lead alloy. While this process is very efficient, it still suffers certain inherent disadvantages which desirably are to be overcome. In particular, the maximum conversion of lead possible is one-fourth of the lead employed as reactant with the other three-fourths necessarily being recovered and re-processed.

There have been attempts to provide organolead compounds by electrolytic procedures. For example, Hein et al., *Z. Anorg Allgem. Chemie*, 141, 161-227 (1924) describes an electrolysis wherein a current is passed through a lead anode into an electrolyte comprising ethyl sodium dissolved in diethylzinc. This procedure operates rather efficiently, but has never been used on a commercial scale for various reasons. For example, inherent in the procedure is the necessity of the difficult preparation of the diethylzinc and ethyl sodium. Further, a disadvantage of the process is that the electrolyte is a highly reactive mixture which is difficult to handle, requiring considerable precaution. Additionally, the conductivity of this system still leaves much to be desired.

An anodic process based upon aluminum triethyl is known; however, while the anode reaction produced tetraethyl lead essentially quantitatively at the anode, the cathode was always subjected to metal deposition which led to objectionable results.

SUMMARY OF INVENTION

According to this invention $KA_1R_2X_2$ is reacted with a lead anode electrochemically in the presence of RX , where R is selected from the group consisting of ethyl, propyl, isopropyl, butyl, and isobutyl and X is selected from the group consisting of bromine, chlorine, and iodine to produce a tetraalkyl lead compound.

DETAILED DESCRIPTION

I have discovered a way to make tetraalkyl lead via an electrochemical process. The process consists of electrolyzing a complex (1:1) of potassium chloride and aluminum diethyl chloride plus ethyl chloride. Lead tetraethyl is formed at the lead anode, while nothing is deposited at a platinum cathode. Ninety-eight percent efficiencies have been obtained, based

on the lead loss. It was established that a hydrocarbon-soluble lead compound was formed. This was shown by flame photometry to be tetraethyl lead.

The $KA_1Et_2Cl_2$ was prepared as follows: a powdered KCl sample (75 g) was dried under a vacuum at $150^\circ C.$ for 24 hours, then placed in the dry box where dry nitrogen was admitted to the evacuated flask. The KCl was then transferred to a 2-liter, three-neck flask, whereupon 200 cc of sodium-dried hexane were added. A glass stirrer was used to keep the flask agitated. A dropwise addition of a room-temperature mixture of 126 cc of A_1Et_2Cl and 126 cc of dried hexane was made using a dropping funnel. After the addition, the hexane was distilled and removed as the product was heated to $80^\circ C.$ and held at this temperature for 2 hours. Upon cooling, the product crystallized at about $58^\circ C.$

The electrical setup was a very simple one which consisted of a D.C. power source, a milliammeter, and the electrolytic cell in series. The current used was constant and usually in the order of 20 ma. A simple measurement of the time the current flowed gave us the number of coulombs and, from that, the number of electrical equivalents used in the experiment. Comparisons could then be made with the equivalents of lead lost from the anode, or the equivalents of aluminum gained by the cathode. For low temperatures, a glass cell was used. At temperatures greater than $20^\circ C.$, due to the higher vapor pressure of ethyl chloride, a small stainless steel bomb of 250-cm^3 capacity was utilized. In some experiments, the vapor pressure of ethyl chloride reached 100 psi. The bomb was fitted with removable electrodes which were led in by packing seals capable of holding 1,000-psi pressure. A glass liner with a dividing glass-fritted membrane was used inside the bomb to hold the sample.

After electrolysis, the sample and the electrolyte were removed from the cell. In some cases, the sample was further extracted with pentane to recover hydrocarbon-soluble lead compounds. The electrodes were then washed, first with hexane and finally with acetone, and reweighed to determine their gain or loss in weight. The amount of hydrocarbon-soluble lead material was determined by flame photometry.

While the exact electrode processes of this system are not known, it is believed that the following reactions take place:

50 At the temperatures used, $70^\circ - 90^\circ C.$, the groups attached to the aluminum atom are very labile, and the $A_1Et_2Cl_2$ could, under these conditions, decompose to give A_1Et_2Cl and A_1Cl_3 . Therefore, the total over-all reaction could be given as:

Table 1 shows the results of several experiments using the concepts of this invention.

TABLE 1
A. Electrolysis of $KA_1Et_2Cl_2$ and ethyl chloride

Sample number	Composition of electrolyte ^a (cc.)		Equivalents of aluminum deposited at Cathode $\times 10^3$	Equivalents of lead lost at anode $\times 10^3$	Electrical equivalents used
	$KA_1(C_2H_5)_2Cl_2$	C_2H_5Cl			
1	90	10	Nil	203	174
2	90	10	Nil	180	195
3	90	20	>2	618	637
4	90	20	Nil	580	595
5	90	30	Nil	401	410
6	90	30	>3	332	373
7	90	40	Nil	375	385
8	90	40	Nil	380	395
9	90	None	225	220	230
10	90	None	235	228	242

^a A hydrocarbon-soluble lead compound was produced in each electrolysis.
Electrolytic conditions: Temperature $70^\circ C.$ with a platinum cathode and lead anode.
Pressure 60 p.s.i. (with $EtCl$).
Voltage ~5 volts.
Amperage 20 ma.

Suitable compounds for use in this invention are those having the formula $KAlR_2X_2$ and RX where R is selected from the group consisting of ethyl, propyl, isopropyl, butyl and isobutyl, and X is selected from the group consisting of bromine, chlorine and iodine. The preferred materials are $KAlEt_2Cl_2$ and $EtCl$. The RX compound should be present in the range of about 10-30 wt. percent, based on the $KAlR_2X_2$ compound.

Suitable cathode materials are those metals which are inert to the system, such as, for example, platinum, nickel and titanium.

While the system can operate without a solvent, certain solvents, such as N,N -dimethylformamide, acetonitrile and N -methyl pyrrolidone, are useful in that they decrease the vapor pressure and help stabilize the product.

The reaction should be carried out at a temperature range of about 60° to about 105° C., with a preferred temperature of about 70° C.

Pressure of the system will vary depending upon the temperature and the amount of RX present, with the preferred pressure being about 60 psi.

Having thus described the invention by providing specific examples thereof, it is to be understood that no undue restrictions of limitations are to be drawn by reason thereof and that many modifications and variations are within the scope of the invention.

What is claimed is:

1. A process for the electrochemical production of tetraalkyl lead compounds which comprises passing an electric current through a cathode, an electrolyte and a lead anode, the electrolyte consisting essentially of $KAlR_2Cl_2$ and $EtCl$ where R is selected from the group consisting of ethyl, propyl, isopropyl, butyl and isobutyl, forming thereby a tetraalkyl lead compound at the anode and withdrawing said tetraalkyl lead compound from the electrolyte.
- 5 2. The process of claim 1 wherein said electrolyte consists essentially of $KAlEt_2Cl_2$ and $EtCl$.
3. The process of claim 1 wherein said cathode is a metal selected from the group consisting of platinum, nickel and titanium.
- 10 4. The process of claim 1 wherein the reaction is carried out in a solvent selected from the group consisting of N,N -dimethylformamide, acetonitrile and N -methyl pyrrolidone.
5. The process of claim 1 wherein said $EtCl$ compound is present in the range of 10 to 30 wt. percent based on the $KAlR_2X_2$ compound.
- 20 6. The process of claim 1 wherein said reaction is carried out at a temperature between about 60° C. and about 105° C.
7. The process of claim 1 wherein said reaction is carried out at about 70° C.
- 25 8. The process of claim 1 wherein said $KAlR_2Cl_2$ is prepared by reacting KCl with AlR_2Cl .
